(57) **CLAIM**

The ornamental design for a basket for cooking, as shown and described.

DESCRIPTION

FIG. 1 is a perspective view of a first embodiment of a basket for cooking showing my new design;
FIG. 2 is an exploded perspective view thereof;
FIG. 3 is an exploded front view thereof;
FIG. 4 is an exploded rear view thereof;
FIG. 5 is an exploded left side view thereof;
FIG. 6 is an exploded right side view thereof;
FIG. 7 is a top view thereof in a non-stacked state that first and second portions of the basket are not stacked on top of each other;
FIG. 8 is a bottom view thereof in the non-stacked state;
FIG. 9 is a perspective view of a second embodiment of a basket for cooking showing my new design;
FIG. 10 is a front view thereof;
FIG. 11 is an exploded perspective view thereof;
FIG. 12 is an exploded front view thereof;
FIG. 13 is an exploded rear view thereof;
FIG. 14 is an exploded left side view thereof;
FIG. 15 is an exploded right side view thereof;
FIG. 16 is a top view thereof in a non-stacked state that first and second portions of the basket are not stacked on top of each other; and,
FIG. 17 is a bottom view thereof in the non-stacked state.
